UNITED STATES PATENT OFFICE

ELMER O. BEARDSLEY, OF CHICAGO, ILLINOIS, ASSIGNOR TO THE BEARDSLEY & PIPER COMPANY, OF CHICAGO, ILLINOIS, A CORPORATION OF ILLINOIS

MACHINE FOR HANDLING MOLDING SAND

Application filed October 8, 1928. Serial No. 311,115.

The invention relates to apparatus for handling sand delivered to molding machines. In foundries, it frequently occurs that scrap or pieces of metal become mixed with the sand that is removed from moulds, which must be separated from the sand before it is delivered to a molding machine of the projector type, to prevent injury to the machine.

The primary object of the invention is to provide improved apparatus for handling the sand in which a magnetic separator is disposed to act upon the sand as it is discharged by an elevator in sufficient quantity to keep the projector supplied, in transit to the projector. Heretofore, it has been the practice to continuously rotate the separator drum in the direction of travel of the sand, to separately discharge the scrap.

In the present invention, the drum is intermittently operated so that the magnetic scrap or parts to be separated from the sand will be intermittently moved out of the magnetic zone and separately discharged from the sand during these intermittent movements. This results in a more effective separation of the scrap from the sand, particularly when a large volume of sand is passed over the drum.

Other objects of the invention will appear from the detailed description.

The invention consists in the several novel features hereinafter set forth and more particularly defined by claims at the conclusion hereof.

In the drawings: Fig. 1 is a side elevation of a portion of a molding machine, having the invention embodied therein. Fig. 2 is a horizontal section on line 2—2 of Fig. 1. Fig. 3 is a vertical longitudinal section. Fig. 4 is a vertical section through the separator drum.

The invention is exemplified in connection with a channelled supporting column or standard 7 which may be mounted on a portable molding machine of the tractor type set forth in Patent No. 1,408,796. The molding sand is elevated from a pile on the floor by an elevator comprising a chain 8, the links of which have secured thereto buckets 9. This chain is usually driven by a sprocket at the lower end of the machine, as exempli-

fied in the aforesaid patent, and its upper end is guided by a pulley 10 mounted on a shaft 11 which is suitably supported from the column 7. The downwardly travelling reach of the chain and buckets travel in the channel of the column 7. At the upper end of the column, there is formed a discharge hood or chute 12. The material from the buckets is discharged downwardly onto a deflector plate 13 in the hood. The drum 14 of a magnetic separator is mounted so one side thereof will be disposed below plate 13, and the sand discharged from the buckets will be delivered onto the other side of the drum which rotates downwardly to discharge the sand into a conveyor chute 15. The drum comprises a peripheral wall 14^a and sides 14^b which are rotatably mounted on a stationary shaft 16. The side walls of hood 12 are extended downwardly at the sides of the drum to confine the sand to the drum, and the outer wall 12^a of the hood is spaced from the discharge side of the drum to permit the sand to be discharged downwardly over the drum. A baffle 17 is spaced from one side of the drum to deflect the sand toward the discharge side of the drum. Shaft 16 is supported by brackets 22 which are secured by bolts 23 to column 7. Said shaft is secured against rotation by caps 24 which are adapted to clamp, by means of bolts 26, the ends of the shaft, in the angular recesses 25 in the ends of said bracket. A stationary magnet 19, comprising a core and suitable windings, is fixedly secured to shaft 16 inside of the drum. Conductors 20 lead to and from said windings, and extend through a hole in said shaft. This magnet is adapted to attract and hold on the drum, magnetic material, such as cast iron scrap metal parts which, in practice, frequently become mixed with, or left in, the molding sand when it is cleaned out of flasks. The magnet is shaped to be effective upon the scrap throughout an arc of approximately 180°, which includes that portion of the drum with which the descending sand contacts, and a sufficient distance beyond the point of discharge of the sand to release the scrap and separately discharge it into a chute 21 secured on the column 7.

In supplying sand to molding machines of the projector type, it is necessary to handle large quantities of sand in the separator, for example, from seven to twelve cubic feet per minute. A desideratum in handling sand for this purpose is to operate the drum at a sufficient speed to carry the scrap so it will be separately discharged from the sand, while at the same time, operating the drum so that its periphery will not accelerate the movement of the sand and scrap sufficiently to render the magnet inefficient in separating the scrap from the sand. For this purpose, mechanism is provided to rotate the drum intermittently or step-by-step. This mechanism comprises a shaft 28 mounted in bearings 29 which are secured by bolts 29' in brackets 22, a sprocket wheel 30, keyed to drive shaft 28, and having its teeth engaged by the upwardly and downwardly reaches of chain 8, to continuously rotate said shaft, an eccentric or wrist pin 31 on one end of shaft 28, a pawl 32 pivoted to said pin, and a ratchet-wheel 33, which is keyed to the hub of one of the drum-sides 14^b, and is engaged and intermittently advanced by the free end 34 of said pawl, which rides on the wheel. The wrist-pin alternately operates the pawl to engage a tooth on the ratchet-wheel and rotate or advance the drum one step, and to idly retract the pawl. During the retraction of the pawl, the drum remains stationary. This mechanism moves the periphery of the drum, during the operative strokes of pawl 32, so the attracted scrap will pass out of the magnetic field, and be thrown into chute 21. The drum remains stationary during the retractile strokes of the pawl to insure the attraction of the scrap in the sand. This is of importance in handling bucket-loads of molding sand in large quantities, as is necessary to keep a molding machine supplied with sand for continuous operation, because the slowly and intermittently moving drum does not accelerate the movement of the sand and scrap. Such acceleration renders the separation inefficient.

The invention exemplifies a sand handling apparatus which is particularly adapted for large quantities of molding sand, and in which the separating drum is intermittently operated to attain the advantages aforesaid.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a machine for handling molding sand, the combination of a conveyor comprising an endless chain and buckets, a magnetic separator comprising a rotatable drum to which the sand is delivered by the buckets, and a

stationary magnet in the drum, and mechanism for intermittently operating the drum to discharge separately scrap or metal mixed with the sand, comprising a sprocket-wheel engaging and driven by the chain.

2. In a machine for handling molding sand, the combination of a conveyor comprising an endless chain and buckets, a magnetic separator comprising a rotatable drum to which the sand is delivered by the buckets and a stationary magnet in the drum, and mechanism for intermittently operating the drum to discharge separately scrap or metal mixed with the sand, comprising a sprocket wheel engaging and driven by the chain, and an eccentric pin operated by the sprocket.

3. In a machine for handling molding sand, the combination of a conveyor comprising an endless chain and buckets, a magnetic separator comprising a rotatable drum to which the sand is delivered by the buckets and a stationary magnet in the drum, and mechanism for intermittently operating the drum to discharge separately scrap or metal mixed with the sand, comprising a sprocket wheel engaging and driven by the chain, an eccentric pin operated by the sprocket, a pawl operated by said pin, and a ratchet-wheel on the drum and engaged by the pawl.

4. In a machine for handling molding sand, the combination of a column, a conveyor comprising an endless elevator chain and buckets, a magnet separator comprising a rotatable drum to which the sand is delivered by the buckets and a stationary magnet in the drum, a shaft on which the magnet is mounted, mechanism for intermittently operating the drum to discharge separately scrap or metal mixed with the sand, comprising a sprocket-wheel engaging and driven by the chain, and brackets secured to the column, in which said mechanism and said shaft are mounted.

5. In a machine for handling molding sand, the combination of a supporting structure, a magnetic separator mounted on said structure and comprising a rotatable drum and a stationary magnet in the drum, a conveyor for delivering the sand to the top part of the drum including a continuously driven element, and mechanism driven by said element for intermittently rotating said drum.

6. In a machine for handling molding sand, the combination of a supporting structure, a magnetic separator mounted on said structure and comprising a rotatable drum and a stationary magnet in the drum, means for delivering the sand in successive loads to the top part of the drum including a series of buckets and an endless chain, and mechanism connected to be driven by the chain for intermittently rotating the drum.

Signed at Chicago, Illinois, this 4th day of October, 1928.

ELMER O. BEARDSLEY.
